J. GRIFFIN.
APPARATUS FOR VAPORIZING HYDROCARBON LIQUIDS FOR
ILLUMINATING.

No. 42,469.

Patented Apr. 26, 1864.

Jonathan Griffin

UNITED STATES PATENT OFFICE.

JONATHAN GRIFFIN, OF MERIDEN, CONNECTICUT.

IMPROVED APPARATUS FOR VAPORIZING HYDROCARBON LIQUIDS FOR ILLUMINATING.

Specification forming part of Letters Patent No. 42,469, dated April 26, 1864.

To all whom it may concern:

Be it known that I, JONATHAN GRIFFIN, of Meriden, in the county of New Haven and State of Connecticut, have invented new and useful Improvements in Apparatus for Vaporizing any Hydrocarbon for Illuminating Purposes; and I do hereby declare the following to be a full, clear, and exact description of the same, when taken in connection with the accompanying drawings, and the letters of reference marked thereon, and which said drawings constitute part of this specification, and represent, in—

Figure 1, a side view; Fig. 2, a top view; Fig. 3, a longitudinal section cutting through on $z z$, Fig. 5; Fig. 4, the same as Fig. 2, with top removed; and Fig. 5, a transverse section cutting through $x x$, Fig. 2.

Same letters and characters indicate like parts in the several figures.

I am aware that in vaporizing petroleum, naphtha, or other hydrocarbons for illuminating purposes atmospheric air has been blown over and through the naphtha by being carried below its surface. I am also aware that for the purposes of filtration the naphtha has been passed through a sponge into the apparatus, and that, also, the atmospheric air has been forced through suitable material saturated with the naphtha or other hydrocarbon. To these things I of course lay no claim.

My invention relates, first, to an apparatus for distributing the atmospheric air under the surface of the naphtha, so that vaporization may take place more quickly and uniformly than when freed in a considerable body underneath it and to prevent bubbling as it rises through the liquid, and, in connection with the apparatus, a bright-metal condensing-plate, for collecting the impurities and the drip from the regulator, so as to carry them back to the apparatus.

When the atmospheric air is first admitted to the chamber containing the fluid (fresh naphtha) instant and powerful vaporization commences, which, if not properly checked, causes great pressure upon the burners, and as suddenly as it commences as suddenly the pressure subsides to a certain and nearly equal pressure, or an unequal pressure or flow from the air-forcing apparatus will cause an unequal pressure and unsteady flow of gas at the burner.

The second part of my invention is principally designed to overcome this sudden, undesirable, or unequal flow of gas, and consists in placing a sponge or similar porous elastic substance in a chamber through which the gas must pass upward in its passage from the vaporizing apparatus. A sudden flow of the gas from any cause compresses the sponge or similar substance, which compression retards the passage through the sponge, so that the greater the pressure upon the sponge or its equivalent the (proportionately) less freely the gas or vapor can pass through the sponge or the equivalent substance employed for equalizing the pressure or flow. I find the sponge also useful for another object of great if not equal importance. The sponge naturally contains and retains a certain degree of moisture, which serves to condense the vapor in its passage through it and thus cleanse the vapor from such impurities or particles as may have escaped the action of the condenser-plate.

To more fully describe my invention, in the accompanying drawings, A is a box or case, constructed of metal or any other suitable material and of dimensions in proportion to the quantity of gas to be generated therein. I place an air-chamber, V, within the said box and resting on or near the bottom of the same, (see Figs. 3 and 5,) its sides perforated. The perforations at the center are small and gradually increase in size toward the ends, for the purpose hereinafter shown.

D is a conductor, leading to the said air-chamber, through which atmospheric air is forced to the air-chamber by means of any known device for the purpose. Above the air-chamber I place a metallic plate, C. It may—and I prefer to have it—rest upon the air-chamber. The said plate C should nearly fill the case, but must leave a narrow space around its edge, as shown in Figs. 3 and 5. Above the plate C, I place a second plate, E, resting upon proper supports, and placed so as to come below the surface of the fluid with which the case is to be partially filled. The said plate E should be nearly or quite as large as the interior of the case, (see Figs. 3 and 5,) and finely perforated over its whole surface, as shown partially perforated in Fig. 4, or a network or web of wire might answer the same purpose, the object of which will be fully shown

hereinafter. Above said perforated plate E, I divide the space into two parts by a perforated partition, F, perforated in like manner as the plate E and shown partially perforated in Fig. 5, and in one of the divisions thus formed I place a bright-metal or condenser plate, G, which fills the space, (see Fig. 3,) supported at one side by the partition F, which need not extend below the said plate G, excepting as it serves to support the said plate. This said plate G must be placed above the fluid, and the perforated partition F extends from the plate G to top or cover H, which is closely secured and properly packed, to prevent the gas or vapor escaping from the case. Over the condenser-plate G, I place a dome or equalizing-chamber, I, between which and the condenser-plate I place a perforated plate, a. Above the plate a I set in the dome a fine network or gauze of wire, c. This lies free in the dome. Near the top of the dome I fix another perforated plate L, and at the top of the dome I form the outlet N for the gas to pass off for consumption.

The space S, between the gauze or net-work c and the upper perforated plate, L, I fill with a coarse sponge or some substance of a similar capacity. Hazel shavings are a very good equivalent, but from experiment I as yet prefer sponge to anything I have tried.

My apparatus thus complete, I fill (partially, say to the line denoted in blue, Fig. 3) with petroleum, naphtha, or other hydrocarbon. The fluid should not be below the plate F. Now, force atmospheric air through the conductor D to the air-chamber B, which through the perforations in its sides distributes the same through the whole of the fluid. The perforations in the air-chamber are made small at the center and gradually increase, so as to equally distribute the air; for as the pressure is greater at or near the center, the perforations at that point are small and the pressure diminishing as the air flows from the center, so the perforations increase in size in like proportion. The atmospheric air thus distributed rises around the edge of the plate C through the fluid, and would naturally cause the fluid to bubble or be otherwise agitated, which greatly retards vaporization or otherwise injuriously affects it—vaporization being best accomplished and most perfect when the fluid is in a state of rest. To prevent such agitation the perforated plate E is introduced, which entirely and perfectly accomplishes the object. In its passage up through the fluid, the atmospheric air becomes fully impregnated with the illuminating portion of the hydrocarbon which requires to be purified by condensation. For this purpose the vapor or gas is passed through the upper part of the partition F over the condenser-plate G. This

said plate is bright and smooth, and in the flow of the vapor over it condenses, so that the impurities fall or adhere to the plate, and from thence run back to the fluid below. From thence the partially-purified gas passes up through the perforated plate a through the sponge S. The sponge naturally retains a degree of dampness, which serves to further condense and more perfectly purify the gas before allowing it to pass on and through the outlet N to the burners or receivers. The condensation drips from the sponge and passes off as from the plate.

The second part of my invention or the equalizer I will further explain. When the sponge lies free the gas will flow more freely through it than when the sponge is compressed, so that when the flow or pressure is increased the sponge is compressed by such increase of flow or pressure so that the gas cannot flow through the sponge so free, and thus prevents any action upon the gas beyond the sponge by undue pressure before it. So if the pressure is lessened the sponge relaxes, to allow the gas to pass more freely through it, thus maintaining an equal pressure upon the gas beyond the sponge. The plate c is placed above the sponge to allow more surface for the gas to pass from the sponge than would be were the sponge to bear against the surface of the dome.

Having fully described my invention, what I claim as new, and desire to secure by Letters Patent, is—

1. The submerged perforated chamber B, for the purpose of more equally and quietly diffusing the atmospheric air through the whole of the liquid, substantially as and for the purpose described.
2. In combination with the submerged perforated chamber B, the submerged plate C, to prevent bubbling or agitation of the liquid, substantially as described.
3. The interposition of a bright-metal condensing plate, G, between the liquid in the apparatus and the regulator or equalizer, for the purpose of collecting and returning the impurities and drip, substantially as herein described and represented.
4. In combination with a vaporizing apparatus, a dome or chamber located between the liquid hydrocarbon and the lights or burners, said dome containing an elastic porous substance that will contract and expand under the varying force of the passing volume of vapor or vaporized air through it, and thus act as an equalizer of the flow of gas, substantially as described.

JONATHAN GRIFFIN.
